Primary Examiner — Kevin Rudzinski(74) *Attorney, Agent, or Firm* — Li & Cai Intellectual Property (USA) Office**CLAIM**

The ornamental design for a “display light,” as shown and described.

DESCRIPTION

FIG. 1 is a perspective view of a “display light” showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle;

FIG. 9 is a perspective view showing the practical usage;

FIG. 10 is another perspective view showing the practical usage; and,

FIG. 11 is yet another perspective view showing the practical usage.

The broken lines shown in the drawings illustrate environmental structures that form no part of the claimed design.
